B. F. BARNES, OF BOSTON, MASSACHUSETTS.

Letters Patent No. 84,405, dated November 24, 1868.

IMPROVEMENT IN OIL-CANS.

The Schedule referred to in these Letters Patent and making part of the same.

To all persons to whom these presents shall come:

Be it known that I, B. F. BARNES, of the city of Boston, in the county of Suffolk, and State of Massachusetts, have invented certain new and useful "Improvements in Oil-Cans," and that the following description, taken in connection with the accompanying plate of drawings, to be hereinafter referred to, forms a full and complete specification of the same.

By the present invention, the nose or nozzle to an oil-can is so constructed in two parts or sections that, in combination with a wire or other stem placed within the oil-passage of the nozzle, such oil-passage can be readily cleared and freed of dirt or any other obstruction which by any possibility may become lodged there.

In the accompanying plate of drawings, my improvements in oil-cans are illustrated—

Figure 1 being a central vertical section through an oil-can, with its nose constructed according to my invention.

Figure 2, a horizontal section, taken in the plane of the line x x , fig. 1.

A, in the drawings, represents the body of an oil-can, having an opening at B to receive the nozzle or nose C.

This nose C is made in two parts or sections, D and E, that are connected or joined together by a screw-thread at F, and when so joined, the one forms a continuation of the other in a taper form, coming to a small head at G, where the oil is discharged from the nozzle.

H, the end of nose C, by which it is screwed into the opening, B, of the can.

I, a flange on one end to the part D of nose C. This flange is around the taper part E of the nose, where it is joined to the part D, and there forms a cup, F², to receive the oil-drippings from the mouth

of the nose C, and thus to retain them from passing down over the body of the can.

J, a wire or stem hung at one end, by its eye, K, to the cross-bar L, upon the inside of the part or section D, near its end, where screwed into the mouth of the body A.

This wire is extended up from the bar I, to and into the taper portion of the nose, a sufficient distance as to afford no obstruction to the passage of the oil through the nose, when the can is used. With this wire thus permanently affixed to the nose, by unscrewing the taper section E of the nose, and forcing it through the other section D, the oil-passage through the taper section can and will be cleared entirely from dirt, &c., if any should have there accumulated, pushing it out at its open end, G, as is obvious.

The advantages of my improvements in oil-cans are obviously many, among which may be mentioned that with the wire or stem-cleaner, the nose can be always cleaned with dispatch, and with no trouble or annoyance, the action of the stem being positive, sure, and effectual, and without danger of breakage within the passage.

Having thus described my improvements, I shall state my claim as follows:

What I claim as my invention, and desire to have secured to me by Letters Patent, is—

The nose C, made in two parts or sections, D and E, in combination with the wire J, secured at one end in section D, and extending by its other therefrom into the oil-passage, through part E, substantially as and for the purpose specified.

B. F. BARNES.
